United States Patent

Des. 236,921
Patented Sept. 23, 1975

236,921

WINE PRESS

Urban J. Louis, Springfield, Ill., assignor to
Gloria D. Louis, Springfield, Ill.

Filed Aug. 28, 1973, Ser. No. 392,369

Term of patent 14 years

Int. Cl. D15—08

U.S. Cl. D94—2

FIG.1

FIG.2

FIG. 3

FIG. 4

FIG. 5

FIG. 6

FIG. 7

FIG. 1 is a front, elevational view of a wine press, showing my new design;

FIG. 2 is a rear, elevational view thereof;

FIG. 3 is a top plan view thereof on an enlarged scale;

FIG. 4 is a bottom plan view thereof on an enlarged scale;

FIG. 5 is a left side elevational view of FIG. 1;

FIG. 6 is a right side elevational view of FIG. 1; and

FIG. 7 is a front elevational view of a modified form of my wine press of FIG. 1 wherein one barrel and a narrower rack have been shown; the other views thereof being similar to those of FIGS. 1-6.

I claim:

The ornamental design for a wine press, as shown and described.
